STOKER

James P. Norton, Worcester, Mass., assignor to
 Riley Stoker Corporation, Worcester, Mass., a
 corporation of Massachusetts

Application June 26, 1930. Serial No. 463,908

9 Claims. (Cl. 110—44)

This invention relates to stokers for furnaces, and more particularly to stokers of the underfeed type in which the fresh fuel is forced in beneath the actively burning fuel bed.

Stokers of this type usually comprise one or more troughs or retorts into which the fuel is introduced by a reciprocating ram or equivalent device. The air for combustion is delivered under pressure through tuyère blocks mounted at the upper margins of the retorts. These tuyère blocks must be fastened firmly in place, and it has been customary in the past to utilize bolts for this purpose. This construction has not proven entirely satisfactory, however, for two men are required to install the bolts, and the bolt threads are so damaged by the heat that the nuts cannot be unscrewed when it is desired to replace the tuyère blocks, and it is necessary to burn off the bolts with an acetylene torch.

It is accordingly one object of my invention to provide an improved fastening means for the tuyère blocks of an underfeed stoker which is so arranged that it will hold the blocks firmly in position and the blocks can be easily installed and replaced when necessary.

In stokers of the multiple retort type, which include a plurality of parallel retorts separated by rows of tuyère blocks, it is sometimes found that the air fails to penetrate sufficiently into the retorts, and the combustion is to a certain extent concentrated in the portions of the fuel bed directly above the tuyère blocks. It has heretofore been proposed to remedy this difficulty by utilizing so-called "plate type" tuyère blocks, which comprise web portions provided with ribs on one or both sides to form tuyère openings, the individual blocks being mounted side by side in planes substantially perpendicular to the upper margins of the retort side walls and the arrangement being such that the jets of air are directed transversely of the retorts. This construction has proven satisfactory in stokers having stationary tuyère blocks, but has been subject to difficulties when applied to stokers of the well-known Riley type in which the sides of the retorts are reciprocated. This reciprocating movement is depended upon to feed the fuel and ash toward the rear of the furnace, and it has been found that when plate tuyère blocks of the usual form are used, the desired feeding action does not occur because the blocks tend to slide through the fuel.

It is accordingly a further object of my invention to provide a plate tuyère block construction which will insure a satisfactory feeding

movement of the fuel and ash when applied to a multiple retort stoker having reciprocable retort side walls.

With these and other objects in view, as will be apparent to those skilled in the art, my invention resides in the combination of parts set forth in the specification and covered by the claims appended hereto.

In accordance with one feature of my invention I provide a tuyère block which is so arranged that it may be inserted in position on its support from one direction only, and I provide a fastening member which is arranged to be deformed while located between a shoulder on the support and a cooperating portion of the tuyère block, and which when deformed serves to lock the tuyère block to its support and to prevent it from being separated therefrom. In the preferred construction, each tuyère block has an integral projection which at assembly is located between and below a pair of undercut lugs on the supporting structure, and a metal ring is placed in contact with the projection and forced into such a shape that it contacts with the lugs also and prevents upward movement of the block. When the invention is to be applied to a stoker having reciprocal retort sides I utilize plate type tuyère blocks shaped to provide abrupt shoulders facing the rear of the furnace, these shoulders being connected by gradually sloping portions. The blocks are preferably shaped to provide a number of identical groups each containing a small number of blocks, and the blocks within each group being progressively higher toward the rear of the group.

Referring to the drawing illustrating one embodiment of my invention and in which like reference numerals indicate like parts,

Fig. 1 is a side view of a stoker applied to a furnace, the parts within the furnace being shown in section on the line 1—1 of Fig. 2;

Fig. 2 is an enlarged section of a portion of the stoker on the line 2—2 of Fig. 1;

Fig. 3 is an enlarged elevation of several tuyère blocks mounted on a supporting bracket;

Fig. 4 is a section on the line 4—4 of Fig. 3;

Fig. 5 is an enlarged section on the line 5—5 of Fig. 4;

Fig. 6 is an enlarged perspective view of one of the fastening members prior to use thereof;

Fig. 7 is a perspective view of one of the supporting brackets for the tuyère blocks; and

Fig. 8 is a detail view of the highest or rear one of the tuyère blocks in a group.

In the drawing I have illustrated my invention

as applied to an underfeed stoker of the multiple retort type. This comprises a fuel hopper 10 of suitable construction which is mounted outside of and adjacent to the vertical front wall 11 of a 5 furnace. A plurality of horizontal cylindrical ram casings 12 are mounted beneath the hopper and arranged to receive fuel therefrom. A suitable ram, not illustrated, is arranged to be reciprocated within each ram casing by a rotatable 10 crank shaft 14, as is well known in this art. This crank shaft is arranged to be rotated at a slow speed to a suitable gear reduction device 16 which may be driven by any desired source of power. The weight of the casings and associated parts 15 may be supported on pipe columns 17 which rest on a concrete floor 18.

A plurality of parallel underfeed retorts 20 extend rearwardly from the front wall 11. These retorts are provided with stationary bottom plates 20 21 which incline downwardly at a slight angle toward the rear of the furnace. The side walls of the retorts are formed by hollow side bars 24 which are arranged to support on their upper surfaces the tuyère blocks 25. These tuyère 25 blocks are arranged in rows extending longitudinally of the stoker between the retorts and they form a support for the fuel bed and deliver air thereto.

In the embodiment illustrated I have shown 30 these side bars as being suitably constructed for horizontal reciprocation. For this purpose each side bar is supported at its forward end on a cylindrical member 26 which is mounted in a slide bearing 28 forming an integral part of the ram casing. Each side bar is arranged to be reciprocated by its corresponding ram through a lost motion connection 30 in a manner well known in this art and fully disclosed in the patent to Riley No. 1,090,651. At its lower and rearward end 40 each side bar is attached to a shoe 32 arranged to slide over the upper plane surface of a base plate 33 which is bolted to a pair of I-beams 35. These I-beams extend transversely of the stoker and rest in suitable pockets in the side walls of the furnace as will be well understood.

The stoker as illustrated is provided with an overfeed grate section 36. This may be of any suitable construction and is mounted on the side bars 24 beneath the lower end of the retort 20. 50 This overfeed grate serves as a tuyère structure to furnish air for the combustion of any unconsumed coke which issues from the lower end of the underfeed retort.

In the rear of the overfeed grate 36 I have illustrated a rocker dump plate 38, the upper and forward end of which is pivotally connected to the shoe 32. The rocker plates rest at their lower ends on rolls 40 suitably mounted at the rear ends of horizontal rack bars 41. A vertical bridge wall 43 is arranged in the rear of the rocker plates and in substantial proximity thereto. The position of the rocker plates 38 in relation to the bridge wall may be adjusted by means of a horizontal shaft 45 mounted in suitable brackets 46 which are bolted to the forward I-beam 35. This shaft carries a series of pinions 48 which mesh with the teeth on the rack bars. It will be understood that the shaft 45 extends through the side walls of the furnace and is arranged to be controlled from a convenient point.

A vertical plate 50 is mounted beneath the front wall 11 of the furnace so as to entirely enclose a space beneath the stoker retorts and form a pressure chamber 52. Air may be supplied to this pressure chamber from any suitable forced

draft apparatus, such as a fan, through a duct 53 which may be provided with a damper 54. Air flows under pressure from the air chamber 52 up through the hollow side bars 24 to the tuyère blocks 25 which deliver it to the fuel bed for 80 combustion.

The present invention is concerned with the construction of the tuyère blocks 25 and the means for fastening them in position on the stoker side bars. In the preferred embodiment illustrated I have shown tuyère blocks of the plate type, each comprising a plate or web portion 56 arranged to be mounted in a plane substantially perpendicular to the upper margin of the retort. The web portions 56 of adjacent blocks are spaced 90 apart so that air may flow between them. In order to direct this issuing air in the desired directions and form high velocity jets which will effectively penetrate into the mass of fuel in the retort, I provide spaced ribs 57 integral with the 95 web of each block and preferably on both sides thereof. These ribs are substantially horizontal so that the air issuing from the tuyères is directed transversely of the retorts. This tends to make the combustion uniform across the width of the 100 stoker and eliminates the relatively inactive portions in the fuel bed which are frequently found directly above the retorts in a stoker of this type. In order to avoid the sifting of fine fuel between the tuyère blocks, I prefer to so arrange the ribs 105 57 that the ribs of adjacent blocks overlap each other, as shown particularly in Fig. 3.

In a stoker of the type illustrated, the reciprocating movement of the side bars is depended upon to feed the fuel and ash toward the rear 110 of the furnace. In order to assist this feeding action, I so shape the tuyère blocks 25 as to provide abrupt fuel pushing shoulders 58 facing the rear of the furnace, these shoulders being connected by gradually sloping portions 59. During 115 the rearward movement of the side bars, the shoulders 58 grip the fuel and carry it positively toward the ash dump, and during the forward movement of the side bars the sloping portions 59 slide easily through the fuel bed without any 120 appreciable tendency to transport the fuel with them.

I prefer to form the shoulders 58 by providing a number of identical groups of blocks, each containing a small number of blocks. In the embodiment illustrated I have shown three blocks 125 in each group, though it will be clear that under some conditions a larger or smaller number may be desirable. The top of each block slopes downwardly at an acute angle with one side of the 130 web, and the blocks within each group are progressively higher toward the rear of the group, so that the shoulder 58 is provided on the end block of each group of blocks. This permits the use of relatively high shoulders without necessitating steep connecting portions which would tend to render the feeding action ineffective. The end block shown in Fig. 8 has its ribs 57 terminating short of the outer edge of the block, but as shown in Figs. 2 and 3 the ribs on the intermediate blocks extend to the edges of the webs 56.

The tuyère blocks 25 are mounted upon L-shaped supporting members or brackets 61, one of which is shown in detail in Fig. 7. Each bracket 145 comprises a relatively high vertical plate 62 and a relatively low vertical plate 63, these parts being joined at their ends by connecting portions 65. A boss 66 is provided at each end of the bracket, in order that it may be bolted to the upper edge of the side bar. When the parts are assem- 150

bled, the low plate 63 is located flush with the wall of the retort. This construction provides an opening 67 in the lower portion of the bracket through which air may flow freely to the tuyères. 5 The brackets may be made of any desired length, but I have found that a bracket arranged to support nine tuyère blocks is of a convenient size to manufacture.

In order to locate the tuyère blocks properly on the brackets and hold them firmly in position, I provide a plurality of spaced lugs 69 which extend over the opening 67 and toward the retort from the upper edge of plate 62, and a plurality of spaced lugs 70 at the upper edge of plate 63 which extend away from the retort and toward plate 62. When a tuyère block is assembled on the bracket, the upper portion 71 of the block overlies and rests upon the upper edge of the plate 62, and the part 73 of the web of the block (Fig. 8) enters for a short distance between the lugs 69, which thus prevent any appreciable lateral movement. A downwardly extending projection 74 on the lower end of the block enters between the lugs 70 and by contact with plate 63 prevents the block from moving toward the retort. The lower rib 57 rests on the plate 63. A thin extension 75 on the thick web of the block contacts with plate 62 to assist in locating the block properly and provides additional surface area over which the air flows, thus cooling the block.

With this construction it will be seen that a tuyère block can be removed only by lifting it straight up until the projection 74 clears the plate 63, whereupon it can be moved horizontally toward the retort. The projections 74 are preferably slightly shorter than the vertical distance between adjacent ribs 57 when the blocks are assembled. This permits any one block to be removed or replaced without disturbing the other blocks.

In order to lock the tuyère blocks in position, I employ a deformable device adapted to be inserted between a lug on the tuyère block and an overhanging shoulder on the support and the parts are so arranged that when the device has been deformed it will engage the shoulder and the lug and prevent movement of the block. As illustrated, I may provide a horizontally extending projection 77 integral with the web of each tuyère block which at assembly is located between and below a pair of the lugs 69. These lugs are undercut as shown in Figs. 5 and 7, and a fastening member 78 is provided which is arranged to be deformed into contact with the projection 77 and the undercut surfaces of the lugs, thereby preventing upward movement of the block. This member 78 is preferably shaped as a ring which may be somewhat elongated in one direction as shown in Fig. 6. Each tuyère block has a vertical opening 79 through the web directly above the projection 77 to permit insertion of the fastening ring. In the higher end block shown in Fig. 8, the opening 79 is formed partly as an open channel. After the block is in place, the ring 78 is dropped into the opening 79 and deformed to substantially the shape shown in Fig. 5 by means of a hammer and a blunt ended punch. The deformed ring is in firm contact with the projection 77 and the lugs, so that the block is held firmly in position on the supporting bracket.

After a tuyère block has been in service for a long period it may become so badly burned as to need replacing. I therefore prefer to make the projection 77 relatively weak, so that it may be

broken off by driving heavily against the ring 78 with a punch and hammer. After this projection has been broken off, the block can be removed. The projection is made sufficiently strong to withstand the blows necessary to deform the ring to the shape shown in Fig. 5.

It will be seen that with this construction the tuyère blocks 23 are firmly held in place on the supporting brackets by the fastening members 78, and when necessary any individual block can be replaced by a new one without disturbing the adjacent blocks. Fuel is delivered to the retorts from the hopper 10 by means of reciprocating rams, and the fuel and ash in the furnace is positively moved toward the dump plates 38 by the propelling action of the reciprocating tuyère blocks 25. The abrupt shoulders 58 prevent the tuyère blocks from sliding through the fuel bed during their rearward movement. The ribs 57 serve to direct the air in jets transversely of the retorts, so that combustion is substantially uniform across the width of the furnace and the efficiency is materially increased.

Having thus described my invention, what I claim as new and desire to secure by Letters Patent is:

1. An underfeed stoker comprising a plurality of parallel underfeed retorts mounted within a furnace and extending toward the rear thereof, tuyère blocks supported at the upper margins of the retort side walls and comprising spaced plates mounted side by side and extending laterally in planes substantially perpendicular to said upper margins, the tuyère blocks being arranged to deliver air to the fuel in directions transversely of the retorts and the blocks being shaped to provide abrupt fuel pushing shoulders facing the rear of the furnace, and means to reciprocate the tuyère blocks longitudinally of the retorts and thus positively advance the fuel and ash toward the rear of the furnace.

2. An underfeed stoker comprising a plurality of parallel underfeed retorts having reciprocable side walls mounted within a furnace and extending toward the rear thereof, tuyère blocks mounted on the upper margins of the retort side walls and comprising spaced web portions mounted side by side in planes substantially perpendicular to said upper margins, the tuyère blocks being arranged to deliver air to the fuel in directions transversely of the retorts and the blocks being shaped to provide abrupt fuel pushing shoulders facing the rear of the furnace which are connected by gradually sloping portions, and means to reciprocate the retort side walls and thus positively advance the fuel and ash toward the rear of the furnace.

3. An underfeed stoker comprising a plurality of parallel underfeed retorts mounted within a furnace and extending toward the rear thereof, tuyère blocks supported at the upper margins of the retort side walls and comprising spaced web portions mounted side by side in planes substantially perpendicular to said upper margins and ribs integral with the web portions which serve to direct air to the fuel in directions transversely of the retorts, the tuyère blocks being shaped to provide abrupt fuel pushing shoulders facing the rear of the furnace which are connected by gradually sloping portions, and means to reciprocate the tuyère blocks longitudinally of the retorts and thus positively advance the fuel and ash toward the rear of the furnace.

4. An underfeed stoker comprising a plurality of parallel underfeed retorts mounted within a

furnace and extending toward the rear thereof, tuyère blocks supported at the upper margins of the retort side walls and comprising spaced web portions mounted side by side in planes substantially perpendicular to said upper margins, the tuyère blocks being arranged to deliver air to the fuel in directions transversely of the retorts and so shaped as to provide a number of identical groups each containing a small number of blocks, the blocks within each group being progressively higher toward the rear of the group so as to form an abrupt fuel pushing shoulder on each group which faces the rear of the furnace, and means to reciprocate the tuyère blocks longitudinally of the retorts and thus positively advance the fuel and ash toward the rear of the furnace.

5. A tuyère structure for a stoker comprising a supporting member having a row of spaced horizontally extending lugs thereon, a plurality of tuyère blocks mounted on the member and each provided with a horizontally extending projection which at assembly is located close to and beneath a pair of the lugs, and a plurality of fastening devices each arranged to be deformed into contact with one of the projections and the adjacent pair of lugs, said parts being so arranged that the tuyère blocks are held in position by the deformed devices.

6. A tuyère structure for a stoker comprising a supporting bracket having a pair of horizontally extending lugs thereon having undercut surfaces, a tuyère block mounted thereon and provided with a horizontally extending projection which at assembly is located between and below the lugs, and a ring which is placed on the upper surface of the projection and deformed into contact with the undercut surfaces of the lugs, thereby preventing upward movement of the block.

7. A tuyère structure for a stoker comprising an L-shaped supporting bracket having an opening in its lower portion through which air may flow, a plurality of spaced horizontally extending lugs on the bracket each having undercut

surfaces, a plurality of tuyère blocks mounted on the bracket and each having a horizontally extending projection located between and below a pair of the lugs, means preventing the blocks from moving horizontally relative to the bracket, and a ring in contact with each projection which is deformed to contact with the undercut surfaces of the lugs, thereby preventing the blocks from moving vertically relative to the bracket.

8. A tuyère structure for a stoker comprising a supporting bracket having a high vertical plate and a relatively low vertical plate which are spaced apart to provide an opening for the flow of air, a plurality of spaced lugs extending laterally from the high plate over the opening which have undercut surfaces, a plurality of spaced lugs extending from the low plate toward the high plate, a plurality of tuyère blocks mounted on the bracket and each having a web portion which enters for a short distance between a pair of the lugs on the high plate, a horizontally extending projection on each block which is located between and below a pair of the lugs on the high plate, a downwardly extending projection on each block which is located between a pair of the lugs on the low plate, and a ring shaped fastening member for each block which is deformed at assembly to contact with the horizontal projection on the block and the undercut surfaces of the corresponding pair of lugs on the high plate.

9. A group of tuyère blocks adapted to be assembled with similar groups and mounted substantially vertically on the side walls of an underfeed retort comprising a plurality of plates each of which has a central web and laterally projecting ribs forming air channels, the top edges of the plates sloping gradually towards one end of the group, and the outer face of the highest end plate having an exposed portion at assembly which forms a fuel pushing shoulder, the vertical faces of the other plates being unexposed.
